UNITED STATES PATENT OFFICE.

DON CARLOS TRAVIS, OF KENOSHA, WISCONSIN, ASSIGNOR TO SIMMONS COMPANY, OF NEW YORK, N. Y., A CORPORATION OF DELAWARE.

EXTENSIBLE BEDSTEAD.

Application filed November 10, 1925. Serial No. 68,102.

My invention relates to extensible bedsteads of the type wherein one section of the bed is a stationary section and the other section is movable from a position overlying the 5 stationary section to a co-planar position, thereby forming a bed of double width.

The object of my invention is to provide such a bedstead wherein the movable section is provided with strong bracing means to 10 prevent the collapse thereof, due to the pull of the bed fabric. Another object is to provide such a bed which will be light in weight, of rigid construction and which will be artistic in its appearance. Other objects and 15 advantages will be understood by references had to the following specification when considered in connection with the accompanying drawings, wherein I have illustrated a selected embodiment of my invention, and in 20 which:—

Fig. 1 is a perspective view showing my bed partly extended.

Fig. 2 is an end elevation showing the bed folded.

Fig. 3 is an end elevation showing the parts 25 partially extended as in Fig. 1.

Fig. 4 is an end elevation showing my bed fully extended.

Fig. 5 is a section on the line 5—5 of Fig. 3, 30 and

Fig. 6 is a section on the line 6—6 of Fig. 2.

Referring now to the drawings, 10 indicates the stationary section and 11 the movable or extensible section of my improved bedstead. 35 The stationary section 10 includes end frames 12 and 13 which comprise legs 14 and 15, cross members 16, and top rail 17 and bed fabric 18 stretched between the said top members 17. The two end frames 12 and 13 are 40 spaced apart by side rails 19 and 19^a on one side and 20 and 20^a on the other side.

The movable section 11 comprises end frames 21 and 22 which are made up of horizontally extending members 23 and downwardly extending legs 24, and bed fabric 25 stretched between the said horizontally extending members 23. The said end frames 21 and 22 are spaced apart by means of side rails 26 and 27 extending between the said 50 downwardly extending legs 24. The movable section is pivotally connected to the stationary section by means of a link 28 which is pivotally connected at its upper end to the end of the horizontal member 23 as indicated 55 at 29, and to the cross member 16 of the sta-

tionary section at a point spaced from the lower end thereof as indicated at 30. In order to maintain the movable section in substantially horizontal position during the folding operation, I provide another link 31 which is pivoted at its ends to the horizontal rail 23 of the movable section as indicated at 32 and to the cross member 16 of the stationary section as indicated at 33.

It will be apparent from an inspection of 60 the drawings that the bed fabric 25 of the movable section will have a strong tendency to pull the horizontally extending rails 23 toward each other, especially at the ends remote from the leg sides which are held spaced 65 apart by means of the spacing bars 26 and 27. To overcome the collapsing tendency created by the bed fabric as above explained, I provide spacing bar 34, secured at its ends to the links 28 as indicated at 35 and 36 above 70 the pivotal connection 30 and spacing bar 37 extending between the lower or free ends of the said links and likewise secured thereto. An additional bracing member 38 extending 75 diagonally from the free end 39 of the link 28 to a point on the spacing bar 34, the said brace being secured at said free end and at a suitable point on the spacing bar as indicated at 40. It will be noted that by pivoting the link 28 at a point spaced from its lower end, 80 I am enabled to provide a diagonally extending brace which straddles the cross member 16 and I am enabled thereby to effectively prevent the collapse of the inner ends of the horizontal rails 23. It is also to be noted 85 that the spacing bar 37 may be dispensed with if desired, and also that I may dispense with the spacing bar 34 and use only the bar 37, in which case I reverse the direction of the brace member 38. In that case the brace may 90 be secured to the link 28 at a point such as indicated at 35 and to the spacing bar 37 at 95 any suitable point.

To assist in the folding or extending of my improved bedstead, I prefer to provide 100 springs 41 and 42. One end of each of these springs may be connected to the legs 14 and 15 of the stationary section frames 12 and 13, as indicated at 43 and 44. The other end of these springs may be connected at the 105 free end of the link 28 as indicated at 45.

It will be obvious that in the extending operation the spring 42 will, at the beginning of the operation, exert a considerable tension 110 on the free end of the link 28 to raise the mov-

able section to its highest position, at which time, it is approximately balanced in its pulling power by the spring 41. At this point, or when slightly over center, the weight of the movable section tends to quickly and forcibly complete the extending operation, but the spring 41 serves to check this acceleration and acts as a shock absorber, thereby preventing sudden and forceful landing of the legs 24 on the floor.

Ornamental end frames 46 and 47 may be attached to the stationary section by means of angle plates 48 and 49 or by any other suitable means, and suitable corner bracing such as indicated at 50 and 51 on the stationary section 52 and 53 on movable section may be provided.

I am aware that changes in the construction and proportion of parts may be made without departing from the spirit of my invention, and I reserve the right to make all such changes which fairly fall within the scope of the following claims which should be construed as broadly as possible, consistent with the state of the art.

I claim as my invention:

In an extensible bedstead, the combination

of a stationary bed section including end frames each of which is provided with supporting legs and a cross member extending between and secured to said legs, a movable bed section including end frames, and means for movably connecting the end frames of said movable section to the corresponding end frames of said stationary section, said means including links pivotally mounted intermediate their ends on the outer sides of the cross members of the stationary section end frames and pivotally connected at their respective upper ends to said movable section end frames, a spacing bar extending between said links above said intermediate pivots, a tie bar connecting said links below said intermediate pivots, and a brace between each link and the spacing bar, each brace having its upper end secured to the spacing bar inwardly from the adjacent end of said bar, and its lower end portion underlying the cross bar of the adjacent stationary end section and secured to the lower end of the adjacent link to clear the said cross bar during swinging movements of the link.

DON CARLOS TRAVIS.
